UNITED STATES PATENT OFFICE.

LEMUEL C. McCACKEN, OF BRUSH, COLORADO.

WAGON-BODY LIFTER.

1,353,838.

Specification of Letters Patent. Patented Sept. 28, 1920.

Application filed April 24, 1918. Serial No. 230,508.

To all whom it may concern:

Be it known that I, LEMUEL C. McCACKEN, a citizen of the United States, residing at Brush, in the county of Morgan, State of Colorado, have invented certain new and useful Improvements in Wagon-Body Lifters; and I do hereby declare the following to be a full, clear, and exact description of the invention, such as will enable others skilled in the art to which it appertains to make and use the same.

This invention relates to improvements in lifting devices and particularly to devices for lifting the bodies of hay racks from their running gears for the purpose of unloading the racks.

One object of the present invention is to provide a novel and improved device of this character whereby the wagon can be driven over the lifting device and the rack be automatically lifted therefrom.

Another object is to provide a novel and simple means for insuring the operation of the lifting means.

Other objects and advantages will be apparent from the following description when taken in connection with the accompanying drawing.

In the drawing:

Figure 1 is a side elevation of the invention in lowered position, the wagon being arranged thereover.

Fig. 2 is a side elevation of the device showing it in raised position.

Fig. 3 is a rear elevation of the device in lowered position.

Fig. 4 is a rear elevation of the device in elevated position.

Fig. 5 is a top plan view of the device.

Fig. 6 is a vertical transverse sectional view taken on the line 6—6 of Fig. 1.

Referring particularly to the accompanying drawings, 10 represents a pair of vertical spaced posts which are secured in the ground at the point desired. At a suitable distance from these posts 10 there are secured in the ground similar posts 11, the posts 10 being connected to the posts 11 by the longitudinally extending beams 12.

Disposed above the beams 12 are the longitudinal beams 13. Pivotaly connected to the posts 10, at one end, and to the beams 13 at their other ends, are the lifting links 15. Similar links 16 are pivotally connected to the posts 11 and to the other ends of the

beams 13. These links are of such length that when swung upwardly, they will lift the beams 13 into a horizontal position above the stationary beams 12, as clearly seen in Fig. 2 of the drawings. One end of each 60 of the beams 12 extends a suitable distance beyond the posts 11 and has on its upper faces the ratchet teeth 17, the purpose of which will presently appear. Secured to the sides of the beams 12, adjacent the ends 65 thereof, are the spaced strips 18, between which and the said beams, the lifting links are arranged to slide and be guided, whereby the beams 13 will be properly and positively lifted vertically above the stationary 70 beams 12. Pivotaly connected to one end of each of the beams 13 is a pawl 19 which is adapted to engage with one of the sets of ratchet teeth of the beams 12, when the movable beams are elevated, whereby said 75 movable beams will be held in elevated position with the wagon body or hay rack thereon, as seen in Fig. 2 of the drawings. The hay rack is represented by the reference character 20, the front bolster of the wagon, 80 by the character 21, and the rear bolster by the character 22. Pivotaly mounted on each side of the rack is an arm 23, the purpose of which will appear in the description of the operation of the device. On the 85 other ends of the beams 13 there are secured the vertically extending stop blocks 24 against which the front end of the rack is adapted to engage when the wagon is driven beneath the device. 90

In the operation of the device, the wagon, with its load, is driven beneath the device until the rack engages with the blocks 24, when the movable beams 13 will be swung forwardly and upwardly thereby. When 95 the rack has been raised from the running gear to a certain extent, the arms 23 are permitted to engage at their free ends with the forward side of the bolster, when further forward motion of the running gear will exert a forward and upward push on the movable beams, through the means of said arms 23. Thus the movable beams, together with the wagon body will be elevated to the desired height above and free from the running gear of the wagon. 100

When the body of the rack is to be lowered the pawls 19 are released from the ratchet teeth, but such a procedure would result in the sudden falling of the movable 110

beams and said wagon body. To prevent this sudden falling of the body, I provide the following, retarding device whereby the body can be slowly and easily lowered onto the running gear of the wagon. Between the posts 10 and 11 there is secured in the ground a short post 25 on which is pivotally mounted a vertical lever 26 which is connected to the movable beams 13 by means of 5 a link 27. Thus by grasping the lever 26 10 the movable beams 13 can be permitted to swing down without sudden jar.

What is claimed is:

The herein described wagon body lifter 15 comprising spaced posts, a pair of beams fixed across the upper ends of said posts in parallelism, stops outstanding from the beams at points a little forward of each post and a considerable distance rearward of the 20 same, strips connecting said stops and with

them forming guides, links pivoted to the posts and leading upward through said guides, and movable beams carried by the upper ends of said links and adapted to be dropped onto the fixed beams or raised above 25 the same and held by contact of the links with said forward stops; combined with means on the movable beams for engagement by the wagon body to be lifted, a third link pivoted at one end to the midlength of 30 each movable beam, and a control lever pivoted to the other end of this link, for the purpose set forth.

In testimony whereof I affix my signature in the presence of two witnesses.

LEMUEL C. McCACKEN.
